UNITED STATES PATENT OFFICE.

JOSEPH A. WILLIAMS, OF CLEVELAND, OHIO.

MAGNETO.

1,401,571.

Specification of Letters Patent. Patented Dec. 27, 1921.

Application filed February 2, 1920. Serial No. 355,588.

To all whom it may concern:

Be it known that I, JOSEPH A. WILLIAMS, a citizen of the United States, residing at Cleveland, in the county of Cuyahoga and 5 State of Ohio, have invented a certain new and useful Improvement in Magnetos, of which the following is a full, clear, and exact description.

This invention relates to magnetos, 10 especially of the inductor crossed rotor type forming the subject matter of my prior Patent No. 854,321, granted to me on the 21st day of May, 1907.

The principal object of the invention is to 15 decrease the cost of manufacture of magnetos of the above-named type, and to provide a construction which is easy to assemble, which requires relatively little machine work and when assembled possesses to a 20 high degree the feature of rigidity.

Further the invention aims to provide a 25 construction which permits the use of a winding, large in diameter, *i. e.* radially or transversely considered, thus affording better space for insulation.

Still further the invention aims to improve the facilities for oiling the various bearings, and to provide an oiling system wherein 30 lubricant is supplied at one point only, is conducted to, and amply lubricates the bearings of both the rotor and distributor.

The invention may be briefly summarized as consisting in certain novel details of construction, and combinations and arrangements of parts which will be described in the 35 specification and set forth in the appended claims.

In the accompanying sheets of drawings wherein I have illustrated the preferred embodiment of the invention, Figure 1 is a vertical and longitudinal sectional view of my improved magneto; Fig. 2 is an end view looking toward the distributor and circuit breaker end with the circuit breaker cap 40 broken away; Fig. 3 is a transverse vertical sectional view taken substantially along the line 3—3 of Fig. 1; Fig. 4 is a horizontal sectional view through the top part of the magneto, the section being taken substantially along the line 4—4 of Fig. 1; Fig. 5 is an end view of the rotor; Figs. 6 and 7 are perspective views of the two parts of the housing; and Fig. 8 is a sectional view through the housing member of Fig. 7, the 45 section being taken substantially along the

line 7—7 of Fig. 1 looking in the direction indicated by the arrows.

The magneto includes two permanent horse-shoe magnets 10, 10, a rotor shaft 11 supported in bearings 12 of a two-part housing to be referred to presently, this shaft carrying a rotor having two active flux diverting or controlling portions 13 spaced axially of the shaft and separated by a reduced portion 13^a which is surrounded by the stationary windings of the magneto. These windings include a primary 14, and a secondary 15 in a circular casing 16 fitted around the reduced portion of the rotor and supported centrally in a two-part housing, the casing having at the top an upstanding neck 16^a through which is carried a secondary terminal 17 connected in the customary manner to a contact of the distributor rotor 18 having a sleeve or barrel-like extension 18^a journaled in a bearing 19. The distributor is rotated in the customary manner by gears 20 and 21, the latter being on the rotor shaft 11, and the rotary parts of the distributor are inclosed in a distributor cap 22 normally secured in place by suitable clamps 23, and carrying the stationary distributor contacts.

One terminal of the primary 14 is carried axially at the bottom of the machine by a 45 conductor 24, and at its outer end is connected to the equivalent of a binding post screw 25, whose inner end is connected to a conductor 26 carrying a stationary circuit breaker contact, the movable contact being 50 mounted on a pivoted arm 27 shifted by a cam 28 on the rotor shaft. The circuit breaker parts including the contacts and arm 27 are carried by, and are removable as a unit with a cup-shaped casing member 29 fitting 55 into a suitably shaped part of one of the housing members, this casing member 29 being closed by a circular cap 30 which can be removed when the conductor 24 is disconnected and turned to one side. The cap 30 carries a spark advance or retarding arm 31 which can be rotated in the customary manner. The inner edge of this cap has at its inner margin a series of uniformly spaced lugs which fit into notches at the 60 periphery of the breaker casing member 29, and the cap 30 can be initially positioned so that the advance and retarding arm 31 may be positioned on either side of the magneto.

Coming now to the parts in which the present invention is more directly involved, I will first describe the construction of the housing. In this improved magneto the 5 housing which completely incloses the rotor and windings and supports the rotor as well as distributer and circuit breaker is composed of two parts or members 32 and 33 which are fitted together, end to end, the adjacent 10 ends of the two housing parts having a rabbeted joint formed by overlapping interfitting parts indicated at 34 in Fig. 1, and the meeting faces being at substantially the center of the magneto and being in a plane 15 at right angles to the rotor axis. The housing member 33 has an extension 33^a shaped to support and partially inclose the distributer and circuit breaker. These housing members which are formed of non-magnetic 20 material such as brass, have cast integral with them, pole pieces 34 of magnetic material. Each housing member has two pole pieces similarly disposed in the upper half thereof, each pair being set ninety degrees apart and being, of course, completely 25 separated by the non-magnetic material. By reference particularly to Figs. 6 and 7, it will be seen that the inner or adjacent parts of the two housing members have circular 30 recesses 36 to accommodate not only the rotor but the casing 16 inclosing the windings, each side of the casing 16 being adapted to be seated against machined inset shoulders 34^a of the pole pieces 34 as well as against 35 shoulders 37^a formed in the housing members. Between the pole pieces the top portions 40 of the two housing members are notched out as shown at 38 (see particularly Figs. 6 and 7) so that when the two members of the housing are fitted together there is formed a rectangular space of such size and dimensions as to accommodate the 45 standing neck 16^a of the winding casing 16. By reference particularly to Figs. 1, 6, 7 and it will be noted that the top portions of 50 the housing members between the pole pieces are hollowed out, but this is not essential as it is done for the sake of lightness only.

It is to be noted at this point that not only 55 do the adjacent ends of the housing members engage each other, but the extreme ends of the two pairs of pole pieces carried by the two housing members respectively, are in engagement when the two housing members are fitted together so as to form in effect 60 two continuous pole pieces which extend substantially the full length of the rotor.

The opposite sides of the upper portions 65 of both housing members 32 and 33 have rectangular notches 39 to accommodate the lower ends of the magnets 10, 10, these notches extending inward to, and having their bases formed by the outer sides of the pole pieces 34, which outer sides are parallel, and are therefore engaged by the ends

of the magnets when the latter are in position.

When the two housing members are placed end to end in their proper relative positions and are fastened together by bolts 70 40 which are preferably four in number, and extend axially through both housing members which are provided with suitable bolt holes 41 shown in Figs. 5, 6 and 7, the magnets 10, 10 can be placed in position by slipping their lower ends into the notches 39 over the outer faces of the pole pieces. When the magnets are in position they are spaced apart a distance slightly greater than the distance between the shoulders against 80 which opposite sides of the winding casing 16 bear. In other words, the distance between the magnets, axially considered, is slightly greater than the space required to accommodate the windings and their casing. 85 This permits the use of windings of relatively large diameter, which is desirable in order that ample insulating space may be utilized between the turns or layers. In fact, the outside diameter of the winding 90 casing may be substantially as great as the extreme width of the magneto.

When the magnets are placed in position as above described, they are held in their proper positions simply by a clamping band 95 42, (see Figs. 1, 3 and 4) which is slightly wider than the gap between the magnets and is fastened at its lower ends by screws or equivalent means 42^a to opposite sides of the two housing members. 100

Before the magnets are placed in position, a casing or cap 43 is fitted onto the upper part of the two housing members to inclose the usual condenser 44, the distributer connections and oiling tubes next to be described. This casing, which may be formed of sheet metal, is separated from the magnets when they are next placed in position by felt strips indicated at 45. 105

A further important feature of the invention resides in the provision for oiling the bearings. In accordance with the present invention oil is supplied at one point only, this being at the top of the magneto. At this point there is provided a lubricant receiving 110 cup or tube 46 which is normally closed by a cap 47, and which projects up through the top of casing 43, in the space between the magnets and through the magnet clamping strap 42. At its lower end the tube communicates with two tubes 48 and 49. One of these tubes 48 extends down to and communicates with a duct 50 in the end of the housing member 32, which duct leads to the bearing 12 supported in this housing member. 115 The other tube 49 extends in the opposite direction from the tube 48 to the bearing 19 of the distributer. Below the distributer the bearing has a well 51 containing a wick, and leading from this well is a tube 52 120 130

which extends to the rotor shaft bearing 12 supported by the housing member 33. Thus lubricant supplied at one point located at the most convenient part of the magneto 5 passes by gravity to both the rotor shaft and distributor bearings which are all the bearings of the magneto that require lubricant.

Having described my invention, I claim:
10 1. In a magneto, a housing adapted to support a rotor shaft composed of two members adapted to be fitted end to end with their meeting faces arranged transversely of the rotor axis, a pair of pole pieces carried by each housing member, and magnets engaging said pole pieces.

2. A magneto comprising a housing adapted to support a rotor and composed of two members arranged end to end and having 20 their adjacent faces transverse to the rotor axis, pole pieces cast integral with said housing members, and magnets having their ends engaging said pole pieces.

3. In a magneto, a housing, a rotor of the 25 inductor type supported by the housing and inclosed thereby, stationary windings surrounding the rotor and likewise inclosed by the housing, said housing being composed of two parts fitted together end to end with 30 their adjacent faces transverse to the rotor axis, said housing members each having a pair of pole pieces, and a pair of magnets having their ends engaging the outer faces of the pole pieces.

35 4. In a magneto, a housing, a rotor of the inductor type supported by the housing and inclosed thereby, stationary windings surrounding the rotor and likewise inclosed by the housing, said housing being composed 40 of two parts fitted together end to end with their adjacent faces transverse to the rotor axis, said housing members each having a pair of pole pieces cast integral therewith, and magnets having their ends engaging the 45 outer faces of the pole pieces.

5. In a magneto, a housing of non-magnetic material formed in two parts arranged end to end with their adjacent faces transverse to the rotor axis, a rotor supported by 50 said housing, pole pieces cast integral with each housing member, each housing member having on opposite sides notches which extend to the outer sides of the pole pieces, and a pair of magnets having their ends extending into the notches in engagement with the pole pieces.

6. In a magneto, a housing of non-magnetic material composed of two parts fitted together end to end with their adjacent 55 faces transverse to the rotor axis, a rotor

of the inductor type supported by the housing and inclosed thereby, said rotor having a reduced middle portion, primary and secondary windings, and an inclosing casing therefor surrounding the reduced portion of 65 the rotor, the adjacent portions of the housing members being notched out to accommodate a portion of said casing, pole pieces cast integral with the two housing members and having their outer faces exposed at the sides of the housing members, and a pair of magnets having their ends engaging said pole pieces.

7. In a magneto, a housing of non-magnetic material composed of two members 70 arranged end to end with their adjacent faces at right angles to the rotor axis, a rotor of the inductor type with crossed portions at right angles to each other and with a reduced middle portion supported and inclosed 75 by said housing, windings, and a casing therefor surrounding the middle portion of the rotor, said housing members having pole pieces cast integral therewith and provided at their adjacent ends with notched out portions 80 accommodating a portion of said casing, and provided on opposite sides with notched out portions exposing the outer faces of said pole pieces, and a pair of magnets having their ends fitted into said last 85 named notches and engaging said faces of the pole pieces.

8. A magneto comprising a housing, a pair of permanent magnets, a rotor having 90 bearings in the housing, a distributor having a bearing in the housing, and lubricant conducting means having a single inlet opening located between said magnets and extending to the bearings of both the rotor and the distributor.

9. In a magneto, a housing, a rotor having bearings in the housing, a distributor having a bearing in the housing, a pair of permanent magnets above the housing, oil conducting tubes within the magnets, and ducts extending from the tubes to the bearings of both the rotor and distributor, and an oil inlet at the top of the magneto between said magnets and communicating with said tubes.

10. A magneto comprising a pair of permanent magnets, a housing, and a rotor having spaced bearings in the housing, and lubricant conducting means having a single inlet opening located between the magnets 110 and extending to the bearings of the rotor.

In testimony whereof, I hereunto affix my signature.

JOSEPH A. WILLIAMS
